UNITED STATES PATENT OFFICE.

ISAAC MILLER, ELI BECKER, AND SAMUEL EICHENBAUM, OF CLEVELAND, OHIO.

DESIGN FOR A BOTTLE.

Application filed October 20, 1927. Serial No. 23,834. Term of patent 14 years.

To all whom it may concern:

Be it known that we, ISAAC MILLER, ELI BECKER, and SAMUEL EICHENBAUM, citizens of the United States, residing at 6411 Central Avenue, city of Cleveland, in the county of Cuyahoga and State of Ohio, have invented a new, original, and ornamental Design for Bottles, of which the following is a specification, reference being had to the ac-

companying drawing, forming part thereof.

The figure is a side view in elevation of a bottle, showing our new design.

We claim:

The ornamental design for a bottle, as shown.

ISAAC MILLER.
ELI BECKER.
SAMUEL EICHENBAUM.
